US0D1073014S

(12) **United States Design Patent** (10) **Patent No.:** **US D1,073,014 S**
(45) **Date of Patent:** **** Apr. 29, 2025**

(54) **PET WATER DISPENSER CARTRIDGE**

(71) Applicant: **Shenzhen Fanxin E-commerce Co., Ltd**, Guangdong (CN)

(72) Inventor: **Fujie Wang**, Guangdong (CN)

(73) Assignee: **Shenzhen Fanxin E-commerce Co., Ltd**, Shenzhen (CN)

(**) Term: **15 Years**

(21) Appl. No.: **29/984,887**

(22) Filed: **Jan. 15, 2025**

(51) LOC (15) Cl. **23-01**

(52) U.S. Cl.

USPC **D23/209**

(58) **Field of Classification Search**

USPC D23/200, 202, 205, 207, 208, 209, 210, D23/228, 233, 249, 259, 260, 261, 262, D23/313, 323, 365, 366; D24/108, 112, D24/127, 129, 162; D7/400, 667; D9/424, 428, 432, 504, 772, 780; D30/121, 122, 129, 130, 131, 132, 133

(57) **CLAIM**

The ornamental design for a pet water dispenser cartridge as shown and described.

DESCRIPTION

FIG. 1 is a perspective view of a pet water dispenser cartridge showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.
